Mr. Wallace White
ATTY.

UNITED STATES PATENT OFFICE.

BRUNO SCHWARZE, OF BERLIN-CHARLOTTENBURG, GERMANY, ASSIGNOR TO THE FIRM WOLF, NETTER AND JACOBI, OF BERLIN, GERMANY.

WARDROBE.

Application filed January 19, 1921. Serial No. 438,341.

To all whom it may concern:

Be it known that I, BRUNO SCHWARZE, a citizen of the German Empire, residing at Berlin-Charlottenburg, Germany, have invented certain new and useful Improvements in and Relating to Wardrobes (for which I have obtained a patent in Germany dated January 11, 1919), of which the following is a specification.

10 The invention relates to wardrobes and more particularly to wardrobes intended for use in infirmaries, hospitals, factories and similar places in which the persons following their occupations exchange their ordinary dress for one more suited to their work, the latter being taken from the wardrobe and the former being put in its place until required again. As physicians and doctors during their occupation in hospitals 20 and infirmaries come in contact with the patients there is a possibility that the walls of the wardrobe become infected by contact with the working dress and that the infection is transmitted to the street dress subsequently suspended in the wardrobe, and 25 microbes and germs are spread by the wearer of the infected garments. In factories the dirty working dress soils the walls of the wardrobe or cupboard at the inside and the 30 street dress subsequently suspended in them becomes soiled too. The working dress of workmen becomes in course of time very dirty through contact with oil, paint and the like and the wardrobe walls transfer part of this dirt to the street garments which during the working hours are suspended in them.

The fact that these wardrobes or cupboards are as a rule very narrow promotes 40 this transfer of dirt still more. Very often these wardrobes are shared by several men. The garments are then closely packed into the wardrobe and intimate contact with the walls and transmission of grease, paint and the like from the walls to the clothes cannot 45 possibly be avoided.

This invention consists in covering the inner side of the walls of wardrobes and the like by folding flaps or similar appliances, 50 either partly or entirely, in such a manner that after the removal of the working clothes the walls of the wardrobe are covered up before the street garments are hung up in it, so that these garments come in 55 contact only with clean surfaces and the

danger of the transfer of dirt, germs and the like to the street garments is effectively avoided.

In the accompanying drawings the invention is diagrammatically illustrated by way 60 of example.

Fig. 1 shows a cross-section through a wardrobe and

Figs. 2-4 various kinds of folding flaps.

On referring to the drawings it will be 65 seen that at the rear wall *b*, *c*, of the wardrobe the flap *a*, *d*, *e* has a hinge at *d* and covers one side wall as well as one half of the back wall. In the same way the door is fitted with a flap *h* *i* which also covers 70 one half of the inner surface of the door. The hinges *a* and *h* around which the flaps *a*, *d* *e* and *h*, *i* are adapted to swing are disposed vertically at about the middle of the rear wall and the door. Assuming, for instance, that in the drawings the position of the flaps is that which they occupy when the wardrobe is used for the reception of the working clothes, the inner surfaces of the flaps as well as the uncovered parts of the 75 rear and side walls and the door come in contact with the working clothes and become infected or soiled. When a change of clothing takes place and the working clothes are taken out of the wardrobe, the flaps *a*, *d*, *e* and *h*, *i* are brought into the positions indicated in broken lines before the street garments are put into it, so that the flaps now occupy the positions *a*, *f*, *g* or *h* *k* 80 respectively. As will clearly be seen in Fig. 1 90 the formerly uncovered parts of the walls and the door are now covered up and at the same time the previously front surfaces of the flaps have now become the back surfaces. The street garments thus only come 95 in contact with entirely clean surfaces. When after the work is finished the working clothes are again to be disposed in the wardrobe, the street garments are removed again 100 and the flaps are turned back into their original position, that means into the position shown in full lines in Fig. 1 so that the working clothes come only in contact with the already infected or soiled walls.

When fitting this appliance to already existing wardrobes, it is advisable to make the width *a*, *d* and *d*, *e* of the flaps adjustable by constructing them in two or more overlapping parts, as shown in Fig. 2. Such flaps can easily be adapted to various widths 110

and depths of wardrobes. Instead of using rigid flaps, as before described for covering the inner walls and the door of wardrobes, screens of cloth laid in folds may be employed, as shown in Fig. 3. It will be obvious that such expandible and contractible screens may easily be fitted to wardrobes of any size.

The flaps may also be made in several jointed parts, as shown in Fig. 4. In hospitals and infirmaries the flaps may, for instance, be made of enamelled sheet metal, so that they may easily be cleaned and disinfected from time to time. Instead of the flaps roller-blinds adapted to be wound around vertical or horizontal shafts may be employed for covering the walls with the same object in view. Care must, however, be taken that in rolling the blind up its two surfaces do not come in contact. This may be effected by providing the individual staves of the rollers with projecting edges at both ends, so that the two faces of the rolled-up blind are kept at some distance apart. It is obvious that the same results may easily be attained by other means.

Although I have described certain specific constructions by way of example, it will be readily understood, that various changes in the details of the device may be made, within the scope of the claims, without departing from the spirit or sacrificing any advantages of the invention.

What I claim and desire to secure by United States Letters Patent is:

1. The combination, in a wardrobe, of a flap consisting of two articulated portions covering one half of the back wall and one side wall, a hinge at the edge of said flap at about the middle of the back wall around which the said flap is adapted to be swung

into the other half of the wardrobe and a hinged flap covering one half of the inside of the door.

2. The combination, in a wardrobe, of a flap consisting of two articulated portions, each portion comprising two or more parts adapted to slide upon each other, said flap covering one half of the back wall and one side wall, a hinge at the edge of said flap at about the middle of the back wall around which the said flap is adapted to be swung into the other half of the wardrobe and a hinged flap covering one half of the inside of the door.

3. The combination, in a wardrobe, of a flap consisting of two articulated portions, each portion being constructed of folded cloth, said flap covering one half of the back wall and one side wall, a hinge at the edge of said flap at about the middle of the back wall around which the said flap is adapted to be swung into the other half of the wardrobe and a hinged flap covering one half of the inside of the door.

4. The combination, in a wardrobe, of a flap consisting of two articulated portions, each portion comprising a number of parts joined by a flexible connection, said flap covering one half of the back wall and one side wall, a hinge at the edge of said flap at about the middle of the back wall around which the said flap is adapted to be swung into the other half of the wardrobe and a hinged flap covering one half of the inside of the door.

In testimony whereof I affix my signature.

BRUNO SCHWARZE.
In presence of—
EDUARD PEITZ,
KARL TRIER.
